FIG. 5

UNITED STATES PATENT OFFICE.

CHARLES B. TELLING, OF CLEVELAND, OHIO.

HOLDER FOR ICE-CREAM MOLDS.

1,303,990.

Specification of Letters Patent. Patented May 20, 1919.

Application filed December 8, 1917. Serial No. 206,231.

To all whom it may concern:

Be it known that I, CHARLES B. TELLING, a citizen of the United States, and a resident of Cleveland, county of Cuyahoga, and State 5 of Ohio, have invented a new and useful Improvement in Holders for Ice-Cream Molds, of which the following is a specification, the principle of the invention being herein explained and the best mode in which I have 10 contemplated applying that principle, so as to distinguish it from other inventions.

The present invention, relating as indicated to holders for ice cream molds, is more particularly concerned with a holder or 15 framework, in which may be mounted a number of tubes or molds for preliminarily forming the centers of fancy ice cream bricks, it being one purpose of the invention to provide such a holder which will accommodate 20 a large number of such molds and seal the same against the introduction of the ice and brine which is packed therearound to preliminarily freeze the material which is placed in the molds. To the accomplishment 25 of the foregoing and related ends, said invention, then, consists of the means hereinafter fully described and particularly pointed out in the claims.

The annexed drawing and the following 30 description set forth in detail certain apparatus embodying the invention, such disclosed means constituting, however, but one of various mechanical forms in which the principle of the invention may be used.

In said annexed drawings;—

Figure 1 is a side elevation of my improved holder; Fig. 2 is a plan view of the same; Fig. 3 is an end view of the holder; Fig. 4 is a section showing the sealing cups 40 in the bottom of the holder and the tubes or molds received therein, and Fig. 5 is a similar section showing a modification of such sealing cups.

Referring now to Figs. 1, 2, and 3, there 45 is shown a holder in the form of a casing, preferably constructed of sheet metal and provided with a solid bottom 1 and ends 2. On two sides, 3, the covering or metal is extended about half way down to permit of a 50 free circulation of the freezing material through the holder and about the tubes which are to be placed therein, and to facilitate this circulation the ends 2 are provided with a plurality of apertures 4 there- 55 through, as are also the sheets which extend partly down the sides. For convenience

handles 5 are attached adjacent to the top at either end.

On the bottom 1 of the holder are provided a plurality of rows of sealing cups 6, each 60 cup being preferably cylindrical in shape and extending upward from the bottom of the holder a short distance and having its upper edge turned outwardly to form a flange 7. The top 14 of the holder is provided with 65 a number of openings 8 arranged in line with the sealing cups on the bottom and adapted to receive therein a plurality of molding tubes 9 of various shapes, all of 70 which are, however, of about the same over-all dimensions so that they stand substantially vertical and parallel in the holders when their bottoms are in the sealing cups. Between the sealing cups in the bottom are disposed apertures 10 to permit of drainage 75 from off the bottom of the holder and to permit of a free circulation of the freezing material.

In use the sealing cups are first partially filled with melted paraffin 11 (see Fig. 4) 80 and the molding tubes are then set into these cups, the paraffin hardening quickly and acting to seal the lower ends of the various molds and thus to prevent any communication between the interior of the molds and 85 the freezing material, which is circulated or packed about the molds in and around the holder. The material which is to form the centers of the fancy ice cream bricks is then poured into the molds until they are 90 filled and is hardened or frozen by the freezing material that is circulated in and around the holder. To facilitate the filling of the molds, a filling box 15 is employed which is provided with a series of spouts 16 so spaced 95 as to be aligned with the upper ends of the molding tubes 9, so that the tubes may be filled simultaneously. This freezing material may be drawn off from the container in which the holder is held during the freezing 100 process and the molding tubes 9 may then be withdrawn from the holder, washed off with warm water to free the frozen cream or ice from the sides of the mold, and then placed in ice cream molds, which are first 105 partially filled with relatively soft ice cream. After the filled molding tubes 9 have been placed therein the outer molds are completely filled with ice cream. The molding tubes are then withdrawn from the ice cream 110 molds, leaving the material positioned substantially centrally therein. The larger ice

cream molds are then placed under a temperature sufficient to freeze into one solid mass the central portion and the ice cream surrounding it. The general process described above does not form a part of my invention, as this has of course been used for some time, and the present invention relates only to the holder, which is designed to form a convenient means for filling and 10 freezing a large number of molds at once without permitting an excess of the freezing material to be inside of the mold where it would contaminate the ice or ice cream being frozen therein.

15 In Fig. 5, I have shown a sealing cup 12 which is extended to a greater height than the cups 6 and is not provided with any lateral flange and such a form may be used if desired. Both forms 6 and 12 are preferably permanently and rigidly secured to the bottom 1 of the holder.

Other modes of applying the principle of my invention may be employed instead of the one explained, change being made as regards the apparatus herein disclosed, provided the means stated by any of the following claims or the equivalent of such stated means be employed.

I therefore particularly point out and distinctly claim as my invention:—

1. A holder for ice cream molds comprising

Copies of this patent may be obtained for five cents each, by addressing the "Commissioner of Patents, Washington, D. C."

ing a casing member, a plurality of cups mounted therein, the wall of said casing opposite said cups being provided with apertures alined with said cups and adapted to 35 coöperate therewith to receive a plurality of tubular molds and maintain the same in parallelism.

2. A holder for ice cream molds comprising a casing member, a plurality of open 40 cylindrical cups mounted on the bottom of said casing, the top of said casing being provided with a plurality of apertures alined with said cups and adapted to coöperate therewith to receive a plurality of tubular 45 molds and maintain the same in parallelism, and said cups containing sealing material adapted to seal the ends of said molds.

3. A holder for ice cream molds comprising a casing member, a plurality of cups 50 mounted therein, the wall of said casing opposite said cups being provided with apertures alined with said cups and adapted to coöperate therewith to receive a plurality of tubular molds and maintain the same in 55 parallelism, and the other walls of said casing being provided with openings serving to permit circulation through and into the same.

Signed by me, this 6th day of Dec., 1917. 60

CHARLES B. TELLING.
